UNITED STATES PATENT OFFICE.

CARL G. SCHMID, OF INDIANAPOLIS, INDIANA, ASSIGNOR TO INSLEY MANUFACTURING COMPANY, OF INDIANAPOLIS, INDIANA, A CORPORATION OF INDIANA.

MAST HOIST.

Application filed December 12, 1927. Serial No. 239,382.

The object of my invention is to produce a mast hoist of cheap and light construction and of rather limited height capacity for use in the elevation of building materials in the fabrication of comparatively low buildings.

The accompanying drawings illustrate my invention.

Fig. 1, is a side elevation of my improved mast.

Fig. 2, an elevation at right angles to plane of Fig. 1.

Fig. 3, a horizontal section, on a larger scale, on line 3—3 of Fig. 1.

Fig. 4, a side elevation on a larger scale of the top pulley frame.

Fig. 5, an end elevation of the structure shown in Fig. 4.

Fig. 6, a side elevation on a larger scale of the head frame.

Fig. 7, a plan view of a head frame.

Fig. 8 is a side elevation of the elevator carriage and dumping bucket mounted thereon, on a larger scale.

Fig. 9, a plan view of said carriage with the bucket omitted.

Fig. 10, a side elevation, on a smaller scale, of the elevator carriage with the bucket removed, a platform suitable for the elevation of workmen, wheelbarrows and various building materials, substituted therefor.

The mast is composed of a plurality of sections, each section comprising two lengths of commercial channel 10, 10 placed with their flange 10' outwardly projecting and sufficiently spaced to make substantially a square cross section. These channels are secured together by a series of short horizontally spaced channels 11 preferably, though not necessarily, set with their flanges presented outwardly and conveniently and vertically spaced a distance equal to about two reaches of the foot of an operative desiring to climb the mast. The channels 10 are further secured together and braced by diagonally set channel sections 12 placed one between each pair of channels 11 and each having formed therethrough, at a middle point, a foot hole 13, the arrangement being such that the mast may be readily climbed by an operative using the holes 13 and the cross plates 11 as alternate steps or rungs. Plates

11 and 12 may be secured in place by any suitable means.

The several sections are secured together, as at X, in vertical alignment by channels 15 placed in the channels to bridge the joint between two sections and secured by bolts 16.

Detachably secured to the top of the top section of the mast is a pulley head comprising a pair of parallel angle bars 20, 21 and having depending gusset plates 22 to each of which is secured an angle 23 having arms arranged parallel to the flanges of the mast channels and spaced apart, in pairs, a distance slightly greater than the depth of said channels, said flanges being perforated to receive bolts 24 by means of which the structure may be removably secured in position. Journalled between the cross bars 20, 21 are two pulleys 26, 26 over which a hoisting cable 27 may be passed. The upper flanges of the cross angles 20, 21 are perforated to receive guy wire eyes 28 to which guy wires 29 may be secured.

Slidably mounted upon one outwardly projected flange of each channel 10 is a vertically movable carriage 35. The carriage 35 is a framed structure comprising two vertical angle side bars 37, 37 connected at various points by cross angle bars 38, 39 and 40. Secured to the upper ends of the side bars 37 just beneath the upper cross bar 38 is a suspension yoke 41 to which the lower end of cable 27 may be secured. Detachably secured within the angles of the side bars 37 by bolts 42 are slide shoes 43 each provided on its inner face with a notch 44 adapted to receive, laterally interlock with and slide upon flanges of the channels 10, the angles 37 being so spaced that when the parts are assembled as shown in Fig. 9 the carriage will be laterally non-separable from the mast but will be capable of vertical sliding thereon.

Secured to the angles 37 near their lower ends and beneath cross bar 39 are two horizontal channels 45 having their flanges outwardly presented, and braced by the bracing angles 46 connected thereto by the gusset plates 47.

The outer ends of channels 45 are connected to cross channel 54 by plates 50 having downturned ends 51 perforated to receive a shaft

52 upon which is pivotally supported a tilting bucket 53 normally held by gravity, in load supporting position against a stop 58 of frame 35. Bucket 53 near its lip is provided 5 with a roller 55 at each corner.

A material-handling platform P comprises floor boards 56 secured to two angles 57 which may be arranged alongside channels 45 and bolted thereto and to brackets 59.

10 The head frame carries a hopper to which the first section of a chute system may be connected and is of such form that the frame 35 and the dumping bucket carried thereby may be carried upwardly therethrough in 15 order to dump plastic material from the bucket into the hopper.

This head frame comprises a pair of laterally spaced angles 60, 60 of considerable vertical extent connected top and bottom by 20 cross bars 61 and carrying inwardly presented angles 62, 62 spaced from the cross bars 61 to form guide ways 63 for the reception of flanges 10' of channels 10. Secured to the upper ends of angles 60 are horizontal angles 70, 25 connected at their outer ends by the cross angle 71 and at their inner ends with the channel 72, the rectangular frame thus formed being braced by the gusset plates 73, 73 and by the diagonal braces 74 and struts 30 75. The lower ends of angles 60 are connected by the cross channel 76.

Secured to the vertical faces of the angles 70, at their outer ends, are vertical plates 80 which form the upper portion of a hopper 81 capable of delivering into the receiving end of a chute 82 suspended at 83 from the hopper 81.

Secured to the inner faces of each plate 80 are two guides 84, 84 so formed, placed and spaced that, as the bucket nears the upper end of its movement, the rollers 55 will be so guided as to cause the bucket to tilt and dump its contents into hopper 81 and then be free to be moved further upwardly free from the guides and, upon the lowering of the frame 35 to act upon said rollers to return the bucket to load carrying position.

The head frame is laterally braced by cross bracing 85 and may be held in any desired position of elevation by bolts 86 passing through suitable perforations 86' formed in one flange 10' of each channel 10. The head frame may be raised and lowered by means of a suitable cable eye 87.

55 For the purpose of leading cable 27 to the hoist drum I provide an angle section 90 adapted to be detachably secured to either one of the two lower cross channels 11 (which are preferably placed with their flanges uppermost) and to this section 90 I pivotally connect a pulley block 91 under the pulley of which the cable 27 may be led up to the hoisting drum.

In commercial practice the bucket is only of

a few cubic feet capacity and the parts are 65 correspondingly light and, therefore, cheap to manufacture and easy to handle. It is primarily designed for use in connection with comparatively small jobs. It will be understood, however, that I do not intend to unnecessarily limit myself to an apparatus of 70 any particular dimensions.

Further bracing of the structure, other than the bracing from the top frame, may be found to be desirable and for that purpose 75 guy wires 95 may be attached to an arm 100, which may be attached at any desired height.

I claim—

1. A mast hoist comprising a plurality of 80 separably connected sections each composed of a pair of commercial channels secured together web to web in spaced parallelism with their flanges projecting outwardly, and a pulley head separably attached to the upper end of any mast section and comprising 85 downwardly extending lateral spaced elements laterally interlocking with the mast and carrying rotatable rope-supporting and guiding means, the lateral extremes of which project beyond the outer face of the webs of 90 the mast.

2. A mast hoist comprising a plurality of 95 separably connectable sections each composed of a pair of longitudinal commercial channels secured together web to web with their flanges projected outwardly by means of interposed shorter channel sections having their flanges secured to the adjacent faces of the webs of the longitudinal sections, said shorter channels being arranged in two alternate series 100 the channels of one series being substantially horizontal and the channels of the other series extending longitudinally of the structure and provided with intermediate foot-receiving perforations, and said shorter channels being spaced to afford convenient foot supports for a person climbing the mast.

3. A mast hoist comprising a plurality of 105 separably connected sections each composed of a pair of longitudinal commercial channels secured together web to web with their flanges projected outwardly by means of interposed shorter channel sections having their flanges secured to the adjacent faces of the webs of the longitudinal sections, said shorter channels being arranged in two alternate series 115 the channels of one series being substantially horizontal and the channels of the other series extending longitudinally of the structure and said shorter channels being spaced 120 to afford convenient foot supports for a person climbing the mast.

4. A mast hoist comprising a plurality of 125 separably connecting sections each composed of a pair of commercial channels arranged alongside each other with their flanges in parallelism and the edges of the flanges of one channel laterally spaced from the edges of

the flanges of the other channel by means of interposed shorter channel sections having their flanges secured to the adjacent faces of the webs, foot-receiving portions and said shorter channels being spaced to afford convenient foot supports for a person climbing a mast.

5. A mast hoist comprising a plurality of separably connecting sections each composed of a pair of commercial channels arranged alongside each other with their flanges in parallelism and the edges of the flanges of one channel laterally spaced from the edges of the flanges of the other channel by means of interposed shorter channel sections having their flanges secured to the adjacent faces of the webs, and said shorter channels being spaced to afford convenient foot supports for a person climbing a mast.

20. 6. A mast hoist comprising a plurality of separably connectable sections, each composed of a pair of longitudinal commercial channels secured together web to web with their flanges projecting outwardly by means of interposed shorter channel sections, having their flanges secured to the adjacent faces of the webs of the longitudinal sections.

7. A mast hoist comprising a plurality of separably connectable sections, each composed of a pair of longitudinal commercial channels secured together web to web with their flanges projecting outwardly by means of interposed shorter channel sections having their flanges secured to the adjacent faces of the webs of the longitudinal sections, said shorter channels being arranged in two alternate series, the channels of one of the series being substantially horizontal and the chan-

nels of the other series extending longitudinally of the structure.

8. A mast hoist, comprising a plurality of separably connectable sections, each composed of a pair of longitudinal commercial channels secured together web to web with their flanges projecting outwardly by means of interposed shorter channel sections having their flanges secured to the adjacent faces of the webs of the horizontal sections, said shorter channels being arranged in two alternate series and the channels of one series extending diagonally of the structure.

9. A mast hoist comprising a plurality of separably connectable longitudinal sections, each composed of a pair of longitudinal commercial channels secured together in spaced parallelism web to web, with their flanges projecting outwardly by means of interposed shorter channel sections having their flanges secured to the adjacent faces of the webs of the longitudinal sections, a material supporting frame having guide members slidably guided upon one pair of said outwardly projected flanges, and a head frame having guide members slidably guided upon the other pair of said flanges and extending across and beyond and free from the first pair of flanges on the opposite sides of said mast and carrying a hopper spaced from the first pair of flanges to permit the material-supporting frame to pass between the mast and hopper.

In witness whereof I, CARL G. SCHMID, have hereunto set my hand at Indianapolis, Indiana, this 10th day of December, A. D. one thousand nine hundred and twenty-seven.

CARL G. SCHMID.
